Patented Aug. 10, 1915.

UNITED STATES PATENT OFFICE.

HENRY B. STONE, OF PROVIDENCE, RHODE ISLAND.

SIGNALING SYSTEM.

1,149,418.

Specification of Letters Patent. Patented Aug. 10, 1915.

Application filed August 9, 1913. Serial No. 783,905.

To all whom it may concern:

Be it known that I, HENRY B. STONE, a citizen of the United States, and a resident of Providence, in the county of Providence and State of Rhode Island, have invented a new and useful Improvement in Signaling Systems, of which the following is a specification.

My invention relates to signaling systems

10 in which alternating or pulsating current is employed either alone or in conjunction with direct current as in composite telegraph and telephone systems where an interrupted current is used to operate a drop or to operate 15 a relay which actuates a drop, or in superimposed current systems where alternating current having a frequency too high to disturb the direct current apparatus is employed to operate a relay.

20 Relays designed to be operated by alternating currents have been constructed with heavy armatures to prevent chattering or responding to each pulsation instead of responding to a train of pulsations. Such relays have been found sluggish in action and 25 not well adapted to rapid signaling. Relays designed to keep step with the pulsations may be made more sensitive than those designed to respond only to a succession of 30 pulsations.

The object of my invention is to provide means for signaling with alternating pulsating, or periodically-varying currents which shall be rapid, reliable and responsive to 35 very feeble impulses. For this purpose I employ a relay with a light armature capable of vibrating in unison with vibratory currents, and having two contacts, one on either side of the armature, one or more condensers and a battery or other sources of 40 direct current, all connected in such a manner that when the armature makes contact on one side, the condenser receives a charge from the direct current source, and when 45 the armature makes contact on the opposite side the condenser is discharged, while the armature may remain on either contact without permitting the flow of direct current. When the armature is vibrating the 50 condensers draw repeated charges from the direct current source, which may be utilized to energize a second relay or a drop or any other electro-responsive device.

In the drawings which accompany and form 55 a part of this specification I have shown

various arrangements of apparatus and circuits whereby the foregoing object may be realized; but it will be understood that I do not limit myself to the specific arrangements shown, inasmuch as the same result can be 60 accomplished in substantially the same manner by means of other apparatus and circuit arrangements.

In the drawings: Figure 1 is a diagram showing a simple embodiment of my improved signaling system. Fig. 2 is a diagram showing a modification. Fig. 3 is a diagram showing a further modification. Fig. 4 is a diagram showing the preferred form of my invention and Fig. 5 is a perspective view of the magnets shown in Fig. 4.

In all of the figures, A represents a source of alternating, pulsating or periodically-varying current, such for example, as an alternating current generator. K is a circuit-controlling key. R is a resistance. C C' C'' 65 C' C'' are condensers. B B' B'' are sources of direct current, such as batteries. E E' are earth connections. The line wire 1 includes said source of periodically-varying current and key controlling the same, an electromagnet and an earth connection E as indicated, although it will be understood that a metallic return may be employed. The source of current indicated by the battery B', shown in the present instance as earthed at E', is arranged to be connected to the line-wire or other circuit 11 by the armature 8, normally held against its backstop 9 by the spring 10. Between the circuits 1 and 11 are intercalated the devices which constitute the subject matter of the 70 present invention.

In Fig. 1, the contact-members 4, 5, the electro-responsive device 7 and the source of direct current B are serially connected and 75 form a circuit which is open between said contact-members, and the condenser C has one terminal connected to one contact-member and the other to the armature 3.

The electromagnet 2 included in the line wire 1 operates the armature 3, normally held against the contact-member 4 by the spring 6 and is constructed and arranged, as are the armatures 13, 20 and 20', shown 80 in the other figures, to be vibrated when its magnet 2 is energized by periodically-varying current and thus keep step with the electrical pulsations of the line. When the armature 3 is attracted by its magnet and 105

110

2

makes contact with the member 5, the condenser C will be charged by the battery B, and the resulting flow of current, which takes the path B, 5, 3, R, C, 7, B, will energize the electro-responsive device. When the line current decreases sufficiently, the spring 6 will return the armature to the contact 4, discharging the condenser by way of the path C, R, 3, 4, C and the operation will be repeated as long as the line pulsations are continued. The cumulative effect of the rapid pulsations of direct current which are caused to pass through the winding of the magnet 7 in the direction of the arrow will cause the latter to maintain the armature 8 against the terminal contact of the line 11, the magnet 7 being made sufficiently sluggish for this purpose. As indicated by showing a portion of its circuit in dotted lines, the magnet 7, which may operate a re-laying armature as shown, or a telephone drop, or any other suitable device, may be located at a distant station, or it may be near the magnet 2, and it may control the transmission of direct current as shown or may send alternating or pulsating current or currents of any desired character. It will be noted that in the system shown in Fig. 1, as well as in those of the other figures, the armature of the magnet which is in the line circuit may remain on either one of its contacts without permitting the flow of direct current from the source B, but when it is vibrating, the condenser or condensers draw repeated charges from said source and the resulting current flow energizes the electro-responsive device 7. These condenser pulsations may be given any desired strength by regulating the electro-motive force of the battery B and the capacity of the condenser C, and their frequency is determined by the character of the source of periodically varying current A. The device 7, connected in the pathway of the condenser currents, may as shown be an electro-mechanical device responsive to the cumulative effect of several rapidly succeeding pulsations having their strength and frequency thus controlled, and unresponsive to similar pulsations of a considerably lower frequency, since, as above set forth, it is somewhat sluggish. By such means powerful disturbing factors, which lack the required periodicity, may be completely nullified.

55 In Fig. 2, the contact-members 4, 5, the electro-responsive device 7 and the source of direct-current B are serially connected and form a circuit which is open between said contact-members, and said condensers C' C'' each have one terminal connected to a different one of said contact members and their other terminals connected to the armature 13. The magnet 12 is a permanent magnet, so that the armature or tongue 13 is polarized and requires no spring to keep it in

neutral position when alternating currents are used. In this case, the electromagnet of the line circuit consists as shown of two coils 14, 15 with suitable cores arranged on either side of the tongue 13. When the armature is vibrating through the influence of the periodically-varying current on the coils 14, 15, the condensers C' C'' will be alternately charging and discharging and thereby creating a current flow through the winding 75 of the electro-responsive device 7. When the tongue makes contact with the member 5, the condenser C' will be charged by a current which takes the following path: From the battery B to contact 5, tongue 13, 80 resistance R, condenser C', magnet 7 in the direction of the arrow, and thence back to the battery. When the tongue is against the contact-member 4, the current-flow is from the battery B, through condenser C'', resistance R, tongue 13, contact 4, and thus back to the battery through the magnet 7 in the direction of the arrow. These pulsations of direct-current resulting from the successive 90 chargings of the condensers energize the electro-responsive device 7 which may be made sufficiently sluggish to hold the armature 8 against the terminal contact of the line or other circuit 11 as long as the armature 13 is vibrated with sufficient rapidity. 95 At the same time that condenser C' is charging, condenser C'' will be discharging by the way of the path C'', 5, 13, R, C', and simultaneously with the charging of condenser C'', condenser C' will discharge by way of the path C', R, 13, 4, C''.

In the modification shown in Fig. 3, the condensers C' C'', are continuously charged by the direct current source B'' which is connected across their outer armatures. 105 When the battery is first connected as shown, there will be a flow of current resulting from the charging of the condensers, and thereafter there will be no direct current flow in the condenser circuits until the armature 13 is set in vibration by the pulsatory line current. In this case, when the tongue makes contact with the member 5, the condenser C'' will discharge through the winding 18 of the electro-responsive device 7 in the direction of the arrow by way of the path C'', 18, 5, 13, 16, C''. When the tongue makes contact with the member 4, the condenser C' will discharge through the winding 17 of the electro-responsive device in the direction of the arrow by way of the path C', 16, 13, 4, 17, C'. 115

120 It will be noted that when one condenser is discharging as above set forth, the other is being charged, and that the current resulting from such charging will assist in the energization of the electro-responsive device. Thus when the tongue is against the contact 5 and the condenser C' is discharging through the winding 18, the con- 125 130

denser C' will be charging and thereby creating a current flow from the battery B'' through the winding 18, contact-member 5, tongue 13, conductor 16, condenser C' and thence back to the battery in the direction indicated by the arrow, and when the tongue is against the contact 4 and the condenser C' is discharging through the winding 17, the condenser C'' will be charging and thereby creating a current flow from the battery B'' through the condenser C'' , conductor 16, tongue 13, contact 4, winding 17, and thence back to the battery as indicated by the arrow. Thus it will be seen that when one condenser is discharging through one coil in a given direction the other condenser is charging through the same coil in the same direction. It is also evident that either condenser may be disconnected and the pulsations through the single remaining condenser will operate the device effectively if the condenser be of sufficient capacity.

For contact-members I prefer to employ screws, such as shown at 4 and 5 and to adjust the relay by turning the screws so that their points make firm contact with the tongue in its neutral position, and then turning each screw back very slightly, so that the amplitude of vibration of the tongue is very small indeed. In this way I have found that the relay may be made extremely sensitive and that the period of no current may be reduced to a minimum.

The resistance R , which may be included in the condenser circuits of Figs. 1 and 2, to prevent excessive current at the contacts when the condenser is discharged, obviously need not be employed in the system of Fig. 3 where each condenser discharges through a winding of the electroresponsive device.

It will be noted that in Fig. 3, the contact-members 4, 5, both windings 17, 18 of the electroresponsive device 7, and the source of direct current B'' are serially connected and form a circuit which is open between said contact-members, and that the condensers C' C'' are bridged across said source of direct current, each having one terminal connected to a different one of said contact-members through said windings 17, 18, respectively, and their other terminals connected to the armature 13 by the conductor 16.

In Fig. 4 the permanent magnetic field is created by means of a permanent magnet 19, to the proximate ends of which are secured steel springs 20, 20' having their ends slightly separated and in juxtaposition to the preferably-pointed ends of the electro-magnet 21, consisting, as shown, of a bent iron rod having its plane at right angles to that of the permanent magnet 19. Preferably, the spring 20' is insulated from the spring 20, as shown. The variable field is produced by the pulsatory line current

flowing through the windings 14, 15 of the magnet 21. Arranged on either side of the armature or tongue 20 are screw contacts 22, 23, while similar and corresponding contacts 24, 25 are arranged on either side of the armature or tongue 20'.

In the system shown in Fig. 4, the two contact-members 22, 24 on one side of the armatures, the windings 17, 18 of the electroresponsive device, the source of direct current B'' and the two contact-members 23, 25 on the other side of said armatures are electrically connected and form a circuit which is open between the two pairs of contact-members, and each pair of serially-connected condensers C' C'' , and C'_1 C''_1 , are bridged across said source, each condenser having one of its terminals connected to a different one of said pairs of contact-members,—the outer terminals of the condensers C' C'_1 being connected through the winding 17 with the pair of contact-members 22, 24, and the outer terminals of the condensers C'' C''_1 being connected through the winding 18 with the pair of contact-members 23, 25,—the other terminals of the pair of condensers C' C'' being connected to the armature 20 and the other terminals of the other pair of condensers C'_1 C''_1 to the armature 20'.

The energization of the magnet 21 by the pulsating line current produces a cross-field, which causes the attraction of one tongue and the repulsion of the other, so that the tongue 20 will be drawn against the contact 23 and the tongue 20' against the contact 24 when the line current is flowing in one direction, and the tongue 20 against the contact 22 and the tongue 20' against the contact 25 when the line current flows in the other direction. In this case the condensers C'' and C' will discharge through the windings 18 and 17 respectively of the electroresponsive device in the directions indicated by the arrows, when the tongue 20 is against the contact 23 and the tongue 20' is against the contact 24. At the same time the condensers C' and C''_1 are charging and sending current in the same respective directions through said windings and thereby increasing the magnetizing effect of the electroresponsive device. When the positions of the tongues are reversed, the condensers C' C''_1 discharge through the windings 17, 18, respectively, and simultaneously the condensers C'' C'_1 charge and thereby send a current through said windings in the same directions as before.

When the armature 20 makes contact with the member 23 and the armature 20' with the member 24, the paths by which the condensers charge and discharge are as follows: Condenser C'' discharges through the winding 18 by way of the path $C'' a b 18 23 20 e C''_1$. Condenser C'_1 discharges through

4
 the winding 17 by way of the path C' 1 f 20' 24 17 e C' 1. Condenser C' charges through the winding 18 by way of the path B'' a b 18 23 20 e C' d B''. Condenser C'' 1 charges through the winding 17 by way of the path B'' a b C'' 1 f, 20' 24 17 c d B''.

When the armature 20 makes contact with the member 22 and the armature 20' with the member 25, the several paths are as follows: Condenser C' discharges through the winding 17 by way of the path C' e 20 22 17 c d C'. Condenser C'' 1 discharges through the winding 18 by way of the path C'' 1 b 18 25 20' f C'' 1. Condenser C' charges through the winding 17 by way of the path B'' a C'' e 20 22 17 c d B''. Condenser C' 1 charges through the winding 18 by way of the path B'' a b 18 25 20' f C' 1 o d B''. By this arrangement of connections, a source of direct current, two vibrating armatures and four condensers are made to coöperate to produce a strong effect upon the electroresponsive device. Any three of these condensers may be detached and the one remaining condenser will still have connections whereby the armature vibrations charge and discharge said condenser, and in such case both the charges and discharges will be utilized to energize the electroresponsive device connected in the pathway of the condenser pulsations.

Selective signaling may be obtained by means of the apparatus above described by tuning the armatures to respond to a given frequency.

I claim:

1. In a signaling system, a circuit carrying a periodically-varying current, an electromagnet in said circuit, an armature for said electromagnet arranged to be vibrated when said electromagnet is energized by said periodically-varying current, contact-members on either side of said armature, an electroresponsive device, a condenser, and a source of direct current, said contact-members, electroresponsive device and source of direct current being serially connected and forming a circuit open between said contact-members, and said condenser having one terminal connected to one of said contact-members and the other terminal connected to said armature.

2. In a signaling system, a circuit carrying a periodically-varying current, an electromagnet in said circuit, an armature for said electromagnet arranged to be vibrated when said electromagnet is energized by said periodically-varying current, contact-members on either side of said armature, an electroresponsive device, two condensers and a source of direct current, said contact-members, electroresponsive device and source of direct current being serially connected and forming a circuit open between said contact-members, and said condensers each having

one terminal connected to a different one of said contact-members and their other terminals connected to said armature.

3. In a signaling system, a circuit carrying a periodically-varying current, an electromagnet in said circuit, a polarized armature for said electromagnet arranged to be vibrated when said electromagnet is energized by said periodically-varying current, contact-members on either side of said polarized armature, an electroresponsive device, two condensers and a source of direct current, said contact-members, electroresponsive device and source of direct current being serially connected and forming a circuit open between said contact-members, and said condensers each having one terminal connected to a different one of said contact-members and their other terminals connected to said polarized armature.

4. In a signaling system, a circuit carrying a periodically-varying current, an electromagnet in said circuit, an armature for said electromagnet arranged to be vibrated when said electromagnet is energized by said periodically-varying current, contact-members on either side of said armature, an electroresponsive device, two condensers and a source of direct current, said contact-members, electroresponsive device and source of direct current being serially connected and forming a circuit open between said contact-members, said condensers being bridged across said source of direct current and each having one terminal connected to a different one of said contact-members and their other terminals connected to said armature.

5. In a signaling system, a circuit carrying a periodically-varying current, an electromagnet in said circuit, a polarized armature for said electromagnet arranged to be vibrated when said electromagnet is energized by said periodically-varying current, contact-members on either side of said polarized armature, an electroresponsive device, two condensers and a source of direct current, said contact-members, electroresponsive device and source of direct current being serially connected and forming a circuit open between said contact-members, said condensers being bridged across said source of direct current and each having one terminal connected to a different one of said contact-members and their other terminals connected to said polarized armature.

6. In a signaling system, a circuit carrying a periodically-varying current, an electromagnet in said circuit, an armature for said electromagnet arranged to be vibrated when said electromagnet is energized by said periodically-varying current, contact-members on either side of said armature, an electroresponsive device having two windings, two condensers and a source of direct current, said contact-members, both

- windings of said electroresponsive device and said source of direct current being serially connected and forming a circuit open between said contact-members, said condensers being bridged across said source of direct current and each having one terminal connected to a different one of said contact-members and their other terminals connected to said armature.
- 10 7. In a signaling system, a circuit carrying a periodically-varying current, an electromagnet in said circuit, a polarized armature for said electromagnet arranged to be vibrated when said electromagnet is energized by said periodically-varying current, contact-members on either side of said polarized armature, an electroresponsive device having two windings, two condensers and a source of direct current, said contact-members, both windings of said electroresponsive device and said source of direct current being serially connected and forming a circuit open between said contact-members, said condensers being bridged across said source of direct current and each having one terminal connected to a different one of said contact-members and their other terminals connected to said polarized armature.
- 15 8. In a signaling system, a circuit carrying a periodically-varying current, an electromagnet in said circuit, two oppositely-disposed polarized armatures for said electromagnet arranged to be vibrated when said electromagnet is energized by said periodically-varying current, said armatures moving in opposite directions when said electromagnet is energized by current of a given polarity, two contact-members one on either side of one of said armatures and two contact-members one on either side of the other of said armatures, an electroresponsive device having two windings, two pairs of serially-connected condensers and a source of direct current, the two contact-members on the same side of said armatures, the windings of said electroresponsive device, said source of direct current and the two contact members on the other side of said armatures being connected and forming a circuit open between the two pairs of contact-members, each pair of serially-connected condensers being bridged across said source of direct current and each condenser having one of its terminals connected to a different one of said pairs of contact-members, the other terminals of one pair of condensers being connected to one of said armatures and the other terminals of the other pair of condensers being connected to the other armature.
- 20 9. In a signaling system, a source of periodically varying current, means for vibrating an armature in unison therewith, a condenser, a source of direct current, means coöperating with said vibrating armature for charging said condenser from said direct current source when said vibrating armature takes one position and discharging said condenser when said armature takes the opposite position, and an electromechanical device connected in the path of said condenser pulsations, said electromechanical device being responsive to the cumulative effect of several successive pulsations of a given frequency having their strength determined by said source of direct current and the capacity of said condenser and their frequency determined by the character of said source of periodically varying current, and being unresponsive to similar pulsations of a relatively lower frequency.
- 25 10. In a signaling system, a source of periodically varying current and means controlling the transmission of the same, means for receiving said periodically varying current and vibrating two armatures in unison with the same, contact-members for said vibrating armatures, a condenser, a source of direct current, connections whereby said condenser is periodically charged from said direct current source through one of said contact-members and discharged through another of said contact-members when said armature is vibrating and an electromechanical device included in said connections, said electromechanical device being responsive to the cumulative effect of several successive pulsations of a given frequency having their strength determined by said source of direct current and the capacity of said condenser and their frequency determined by the character of said source of periodically varying current, and being unresponsive to similar pulsations of a relatively lower frequency.
- 30 11. In a signaling system, an armature, means for vibrating said armature, an electroresponsive device, two condensers, a source of direct current, and means coöperating with said armature for charging one of said condensers from said source through said electroresponsive device in a given direction and simultaneously discharging the other when said armature has one position and for charging the second condenser from said source through said electroresponsive device in the same direction and simultaneously discharging the first condenser when said armature has its other position.
- 35 12. In a signaling system, an armature, means for vibrating said armature, an electroresponsive device having two windings, two condensers, a source of direct current, and means coöperating with said armature for charging one of said condensers from said source through one of the windings of said electroresponsive device in a given di-

rection and simultaneously discharging the other of said condensers through said winding in the same direction, when said armature has one position, and for charging the 5 second condenser from said source through the other winding of said electroresponsive device in said given direction and simultaneously discharging the first condenser through the last mentioned winding in the 10 same direction, when said armature has its other position.

13. In a signaling system, two armatures, means for vibrating the same in opposite directions, an electroresponsive device having 15 two windings, four condensers, a source of direct current, means coöperating with one of said armatures for changing one of said condensers from said source through one of the windings of said electroresponsive device in a given direction and simultaneously discharging another of said condensers through said winding in the same direction, when said armature has a given position, and other means coöperating with the other 25 of said armatures at the same time for charging a third condenser from said source through the other of said windings in said given direction and simultaneously discharging the fourth condenser through the 30 last mentioned winding in the same direction, when the last mentioned armature has a position opposite to that of the first.

14. In a signaling system, means creating a permanent magnetic field, two oppositely disposed armatures associated with said field, one having a permanent north pole and the other a permanent south pole, means disposed at right angles to said armatures for creating a periodically-varying magnetic 40 field, an electroresponsive device, a plurality of condensers, a source of direct current, and means coöperating with said armatures for charging and discharging said condensers through said electroresponsive device.

45 15. In a signaling system, an armature, means for vibrating the same, contact-members on either side of said armature, an electroresponsive device, a condenser, a source of direct current, and connections whereby no

current flow is obtained from said direct 50 current source when said armature remains on either contact-member and, whereby said condenser is periodically charged from said source through said electroresponsive device when said armature is vibrating. 55

16. In a signaling system, an armature, means for vibrating the same, contact-members on either side of said armature, a condenser, a source of direct current, connections whereby no current flow is obtained 60 from said direct current source when said armature remains on either contact-member and, whereby said condenser is periodically charged from said source through one of said contact-members and discharged 65 through the other contact member when said armature is vibrating, and an electromechanical device included in said connections, said electromechanical device being responsive to the cumulative effect of several periodic pulsations of a given frequency but unresponsive to similar pulsations of a considerably lower frequency. 70

17. In a signaling system, a circuit carrying a periodically varying current, an electromagnet in said circuit, two armatures arranged to be vibrated when said electromagnet is energized by said periodically varying current, contact-members for said armatures, a condenser, a source of direct 80 current, connections whereby said condenser is charged from said source of direct current through one of said contact-members and discharged through another contact-member, and an electromechanical device included in said connections, said electromechanical device having two windings, one of said windings carrying the charges and the other winding carrying the discharges of 85 said condenser. 90

In testimony whereof, I have hereunto subscribed my name this 7th day of August 1913.
